United States Patent Office.

HENRY EDWARD SKINNER, OF LONDON, ENGLAND, ASSIGNOR TO
WILLIAM HOPCRAFT OF SAME PLACE.

Letters Patent No. 95,278, dated September 28, 1869.

IMPROVED STEERING-APPARATUS.

The Schedule referred to in these Letters Patent and making part of the same.

To all whom it may concern:

Be it known that I, HENRY EDWARD SKINNER, of London, England, have invented a new and improved Steering-Apparatus; and I do hereby declare that the following is a full, clear, and exact description thereof, which will enable those skilled in the art to make and use the same, reference being had to the accompanying drawings, forming part of this specification, in which—

Figure 1, sheet 1, represents a perspective view of the base of the outer cylinder, showing the vertical grooves in which the cross-head works.

Figure 2 represents a perspective view of my improved steering-apparatus.

Figure 3 is a perspective view of the inner cylinder with rudder, showing how the lower part of the cylinder is attached to the coupling on the rudder-head.

Figure 4 is a rear elevation of the steering-apparatus, a portion of the outer cylinder being broken away, the helm being hard-a-port.

Figure 5 is a similar view, showing the helm amidship.

Figure 6 is a similar view, showing the helm hard-a-starboard.

Figure 7, sheet 2, is a vertical section of my improved steering-apparatus.

Figure 8 is a horizontal section of the same, taken on the plane of the line $x x$, fig. 7.

Similar letters of reference indicate corresponding parts.

This invention relates to a new steering-apparatus which, while it is of very simple construction, will develop much power, and give full charge of the rudder.

The invention consists in the application of two screws, working one within the other.

Both screws are vertical, and form, in fact, a combination of the rudder-head.

The inner screw is turned by means of the steering-wheel, either directly, or by an interposed system of bevel-gears.

On this screw is arranged a nut, which has projecting arms working in straight vertical slots or grooves, that are formed in an outer casing.

Thereby the nut is caused to move directly up or down when the inner screw is turned.

The arms of the nut fit also through spiral slots formed through a tube that is fitted between the inner screw and the outer shell, and that constitutes the second screw.

As the nut is moved up or down, its arms moving in the spiral slots, will cause the said slotted tube to turn slowly, and as said tube is connected with the rudder, the latter will also be turned.

A very steady and considerable power is thus obtained, and the rudder will be under complete control,

while it cannot be turned by any action of water or otherwise, directly.

This apparatus, while having the outward form of a common rudder-box, will occupy very little space on deck, presents no machinery to interfere with the working of the ship, and none that may be easily injured in action.

A is the external cylinder or casing, and the support of the steering-wheel.

It is, by means of bolts, or otherwise, securely fixed to the deck of the vessel, and is made of cast-iron or other suitable material, of cylindrical or other suitable form.

On the inner face of the shell A, are formed in the same two or more straight vertical grooves $a a$, as shown in fig. 8.

Into the shell A, which has a removable cover, B, is fitted a smaller upright cylinder, C, which is allowed to turn freely, and which is coupled together with the rudder D, as is clearly shown in fig. 3.

The couplings $b c$, on the cylinder C and rudder respectively, mesh into each other, as shown.

E is a screw, suspended vertically within the tube from some arms $d d$ of the case A.

It projects either directly through the cover B of the case, so that the steering-wheel can be horizontally affixed to it, or a bevel-gear wheel, e, may be secured to the screw E, to connect the same with a horizontal shaft, F, on which the steering-wheel G is mounted.

There are as many convoluted or inclined slots f , formed through the cylinder C, as there are grooves a in the shell A.

H is a nut, fitted upon the screw E.

It has projecting arms $g g$, that fit through the slots f , and into the grooves a , as shown in fig. 8.

It will be seen that as the steering-wheel is worked into a rotary direction, the screw E connected with it will, by being turned, raise or lower the nut H, which, by having its arms g work in the convoluted grooves, without being able to turn itself, causes the inner or working cylinder C, which is fixed to the rudder, to rotate, and to thereby give the necessary motion to the rudder.

A pointer, I, may be affixed to the tube C, or to the rudder-head, to indicate at all times the position of the rudder.

In case the apparatus should get out of order, it may be readily detached from the rudder-head, and a lever, J, be inserted in a recess formed in the coupling e , as shown in fig. 7, so that the rudder may be worked by the ordinary chain or rope.

I claim as new, and desire to secure by Letters Patent—

1. The combination of a cylinder with internal flanges d , perforated rest to support the swivelled

screw E, and removable cap B, all constructed to receive the operative-mechanism in the manner shown and described.

2. The combination, with swivelled vertical screw-lugged nut, and corresponding spirally-grooved cylinder, of the gears e e, horizontal shaft F, and steering-wheel G, all arranged to facilitate the management and control of the rudder, as set forth.

3. The combination of the rotating cylinder C, hav-

ing couplings b b appended to its base, with the couplings c c, as and for the purpose specified.

The above specification of my invention signed by me, this 31st day of July, 1868.

HENRY E. SKINNER.
